UNITED STATES PATENT OFFICE.

GEORGE H. TOMLINSON, OF CHICAGO, ILLINOIS, ASSIGNOR TO STANDARD ALCOHOL COMPANY, OF NEW YORK, N. Y., A CORPORATION OF MAINE.

PROCESS OF PRODUCING FERMENTABLE SUGARS FROM CELLULOSIC MATERIALS.

1,032,448.

Specification of Letters Patent.

Patented July 16, 1912.

Continuation of application Serial No. 548,443, filed March 10, 1910. This application filed December 7, 1911. Serial No. 664,373.

To all whom it may concern:

Be it known that I, GEORGE H. TOMLINSON, a subject of the King of Great Britain, residing at Chicago, in the county of Cook 5 and State of Illinois, have invented certain new and useful Improvements in Processes of Producing Fermentable Sugars from Cellulosic Materials, of which the following is a specification.

10 This invention relates to processes of producing fermentable sugars from wood-waste or other cellulosic raw materials, the object of the invention being the provision of a process whereby the wood-waste may be converted rapidly and economically into a product from which the contained fermentable sugars can be quickly and completely extracted in the form of a solution, which is not only sufficiently concentrated for fermentation without further evaporation, but which is practically free from substances exerting a retarding or preventive effect upon fermentation, or contains the same only in such proportion as not to interfere materially with the fermentation.

It has been heretofore asserted that the use of dilute acids exerting a strongly hydrolyzing effect upon cellulose or ligno-cellulose was impracticable as a commercial method 30 for the production of fermentable sugars from wood-waste, for the reason that there were necessarily produced, in conjunction with the true fermentable sugars, products interfering with the normal fermentation of such sugars. For example, in German Patent 111,868, issued May 31, 1900, to Alexander Classen, it is stated: "If the inversion of wood fibers is carried on in the presence of dilute sulfuric acid, with or without the application of steam pressure, there result by-products, which not only prevent the isolation of the dextrose in a technically pure quality, but also very considerably retard or render impossible its fermentation."

45 I have discovered that under proper conditions it is practicable to invert wood-waste or other cellulosic materials by the action of dilute sulfuric or other strongly hydrolyzing mineral acid, as hydrochloric acid, while 50 avoiding the formation in practically objectionable quantities of the injurious or fermentation-inhibiting by-products above referred to. The advantages of the invention may also be secured with other hydrolyzing

agents or acids, as for example chlorin, sulfuric acid or the like.

In order to secure the above results it is practically essential that the charge of wood-waste should be quickly and uniformly heated to the temperature proper for the reaction by which the fermentable sugars are formed, and that after the completion of this reaction, or after it has proceeded to the desired stage, the converted charge should be quickly cooled to or below the boiling point, under normal atmospheric pressure, of the resulting sugar solution. In order that this result may be practically and economically attained the following conditions should be fulfilled.

(1) The charge should be introduced and maintained in such freely permeable condition that it can be quickly and uniformly heated to the proper temperature by the direct introduction of steam into the body of the charge, such direct introduction of steam continuing, as and when required, until the fermentable sugars are formed.

(2) Such prolonged agitation, particularly in rotary digesters, as would give rise to any pronounced flouring or extreme comminution of the wood must be avoided, such comminution leading to collateral reactions resulting in the formation of by-products which interfere both with the extraction of the fermentable sugars and with their subsequent fermentation. The properly digested particles are relatively hard and granular, and are in condition to form a bed or mass which is freely permeable to water and which yields its sugars readily under the usual conditions of diffusion.

(3) The conditions as regards concentration and quantity of acid, and time and temperature of heating must be properly controlled, but may be varied, with mutual correlation, within considerable limits.

(4) The digester-walls should possess in addition to the necessary acid-resisting character, a marked heat-insulating and heat-retaining function, this being essential to securing the best results in the process; for it is possible thereby to avoid such condensation of steam as would interfere with the free permeability and absorptive condition of the mass, and to effect such rapid heating and conversion of the charge that even when large weights are subjected to a slow tum-

bling and mixing action in a rotary digester, no objectionable amount of flouring results. Such walls furthermore retain the heat from one digestion to the next, thereby promoting the rapidity of the conversion and the uniformity of the result, both as regards successive charges and the parts of each individual charge.

(5) It is practically essential that the treatment be applied to large masses of material, comprising usually a ton or more of wood-waste or equivalent substance. Such large masses effectively retain the heat, and thus supplement the action of the heat-retaining digester lining, and render it possible to maintain throughout the complete operation the necessary permeability of the mass.

(6) The steam should be introduced into the interior of the mass to be heated preferably while the latter is in a state of motion. Relatively dry steam is preferred.

In conformity to the foregoing conditions the method may be carried into effect as follows: The digester consists of a large vessel, having a capacity of a ton or more of sawdust, mounted for rotation, provided with a manhole adapted to be hermetically closed after the introduction of the charge, and provided also with a suitable inlet for the admission of steam to the interior of the charge, with a valved outlet of sufficient capacity to permit a rapid reduction of the internal pressure at the close of the conversion, and with the usual indicators of pressure and temperature. The digester is preferably spherical or spheroidal in shape, and is provided with an interior acid-resisting lining which should be of considerable thickness and of a heat-insulating character. A suitable lining for the purpose may comprise acid-resisting brick set in and backed by a suitable acid-resisting cement, which for use with sulfuric or sulfurous acid may comprise wholly or in part a mixture of litharge and glycerin. The total thickness of the heat-insulating lining should be sufficient, under all the conditions of the operation, to prevent such condensation of steam as would result in submerging the mass, or any considerable proportion of it. Exposed metallic linings are not adapted to the purpose of this invention by reason of their high heat-conductivity and their tendency to buckle or separate from the body of the digester. A suitable type of digester is illustrated in my copending application Ser. No. 548,443, filed March 10, 1910, whereof the present application is a divisional continuation. In case a volatile acid or a gaseous hydrolyzing agent is used, it may be introduced with the current of steam into the interior of the mass to be converted; but when a non-volatile acid is used, it is preferred to moisten the material to be

converted with the acid solution, either before or after the material has been charged into the digester. In the latter event the acid solution may be introduced as a spray or shower into the vapor space of the digester after the charge has been heated to 212° Fahrenheit or above by the direct application of steam. Means for operating in this manner are shown in the accompanying drawing, wherein the figure is a vertical, longitudinal section. As therein illustrated, the digester comprises a spheroidal vessel 1 of large capacity, mounted for rotation upon trunnions 2, 3. The shell 4 is of metal, and is internally lined with acid-resisting brick 5 set in a suitable acid-resisting cement 6. A movement of rotation may be imparted to the digester by a worm gear 7.

8 represents the manhole for the introduction of wood-waste and discharge of the converted product, and 9 a blow-off valve for the vapors. Steam for heating the charge is introduced into the interior of the body of material in the digester through a fixed, axially disposed, perforated pipe 10, extending through the trunnion 2, and having blank flanges at the points 11 and 12. Steam and vapors may be blown off through the arched pipe 13, perforated in the vapor space of the digester as indicated at 14, and communicating through the trunnion 3 with the manifold 15. The hydrolyzing agent or acid solution is introduced into the digester through the pipe 16, extending through the arched pipe 13, and terminating in a spray nozzle 17, in position to discharge the hydrolyzing agent upon the surface of the mass to be converted.

Suitable operating conditions are as follows, it being understood that the invention is not limited to the specific details recited, inasmuch as the several factors of time and temperature of the treatment and the quantity and concentration of acid, are to a considerable degree and within reasonable limits mutually convertible: Wood-waste consisting largely of sawdust and usually containing approximately fifty per cent. of moisture is charged into the rotary digester and heated therein by steam applied through the axially disposed perforated pipe, to a temperature of 212° F., or above. The hydrolyzing agent is then introduced, either in the form of vapor with the current of steam, or preferably in the form of a shower or spray of acid solution upon the surface of the moving mass, until an acid concentration of 0.2 to 0.5 per cent. of the total moisture content is attained. The digester is rotated slowly throughout the entire operation. After the introduction of the acid the temperature is maintained, by direct introduction of steam to the interior of the mass as and when required, at a degree fa-

vorable to the production of fermentable sugars, which under the described operating conditions will usually lie between 275° and 325° F. This temperature is maintained for a suitable time, say thirty to forty-five minutes from the first introduction of the acid, and the vapors are then blown off, either through a condensing system for the recovery of volatile wood constituents or reaction products; or into another digester for the purpose of pre-heating the material therein, as may be desired. The cooked mass is then discharged and is preferably extracted by water while still hot, this operation being readily carried out in a diffusion battery of standard type. For the production of ethyl alcohol the extract may be treated in any usual or approved manner, usually involving neutralization by lime, seeding with yeast, fermentation, distillation and rectification. In order to insure a strong and regular fermentation, it has been found desirable to fortify the sugar solution, before fermentation, by adding to it a suitable nitrogenous material, as malt sprouts or the like. The exhausted residue may be partially dried by pressure and burned for fuel or otherwise disposed of.

It is essential, as above stated, that the mass under treatment should remain throughout the conversion, and after the close of the conversion, in a freely permeable state, conducive to quick heating by the internal action of steam, to quick cooling, and to rapid extraction of the fermentable sugars; since any undue prolongation of the heating and cooling stages may lead to the production of injurious by-products. To attain these results excessive condensation of steam must be avoided, since the presence of an excess of water above that required to saturate the wood-waste interferes materially with the operation by diluting the hydrolyzing agent, and reducing the permeability of the mass; and in practice the wood-waste preferably contains, at the time of its introduction into the digester considerably less moisture than is necessary for complete saturation, and the operation is so conducted that the cooked waste is likewise incompletely saturated, that is to say, is capable of absorbing additional water. This effect is primarily due, under the described operating conditions, to the heat-insulating and heat retaining character of the non-metallic lining of the digester. The effect of the character of the lining upon the efficiency of the process is clearly shown in practice by the fact that the best results as regards efficiency of conversion and freedom from by-products tending to hinder extraction and fermentation, are secured only after the digester bodies have acquired their normal working temperature.

65 When the wood-waste is first treated by

means of steam alone to or above the boiling point of water, the hydrolyzing agent^t being thereafter introduced, the heat-retaining and heat-insulating function of the lining is especially important. By its use it is found possible so to limit the condensation of steam in the mass that when the sawdust has attained a temperature suitable for the introduction of the hydrolyzing agent, it is yet in an unsaturated and absorptive state. Under these conditions the acid reagent is quickly absorbed by the particles, and the mass is in excellent condition for effecting the conversion. Preferably the hydrolyzing agent is introduced as a solution at a temperature decidedly below that of the heated wood-waste, under which conditions it is found that a more rapid and intimate absorption is secured. The absorptive condition of the cooked mass is also of great technical importance in facilitating the subsequent extraction of the sugars, the water permeating the entire mass with the utmost readiness and effecting a rapid and substantially complete solution of the conversion products. I am thus enabled to utilize for the extraction the ordinary type of diffusion battery, and thereby to obtain directly sugar solutions adapted for fermentation without the necessity of concentration.

It is to be understood that the process may be modified in various respects, as may be advisable under particular operating conditions. For example, when waste from resinous woods is treated, it may be steamed for the recovery of turpentine as a preliminary step, before the addition of the hydrolyzing agent. This agent being added to the material at a later period of the treatment, and the process continued for the production of fermentable sugars.

I claim:

1. The herein described process of producing solutions of fermentable sugars from wood-waste or other cellulosic raw materials, which consists in charging the moist material into a closed digester, an acid-resisting, heat-insulating and heat-retaining lining, subjecting it therein, admixed with a suitable hydrolyzing agent and in a state of motion, to the direct action of steam under pressure until the reaction has proceeded to the desired extent, thereafter quickly reducing the temperature approximately to the normal boiling point by blowing off steam and vapors, thereby producing a cooked mass which is freely permeable, transferring said cooked mass to a diffusion battery, and extracting the water-soluble conversion products.

2. In a process of producing fermentable sugars from wood-waste or other cellulosic raw materials, the step which consists in converting the wood waste, admixed with a suitable hydrolyzing agent and subject in

- a freely permeable condition to the direct action of steam under suitable pressure, in a closed vessel having an acid-resisting, heat-insulating and heat-retaining lining.
5. 3. The process of producing fermentable sugars from wood-waste or other cellulosic raw materials, which consists in heating the mass, in a freely permeable state and in presence of a suitable hydrolyzing agent, by
10. the direct action of steam admitted to the interior thereof, until the fermentable sugars are formed, and so confining the heat that the mass is maintained throughout the entire operation in an unsaturated and
15. absorptive condition.
4. The process of producing fermentable sugars from wood-waste and other cellulosic

raw materials, which consists in heating the mass, in a freely permeable state, by the direct action of steam, thereafter disseminating through it a suitable hydrolyzing agent, and continuing the heating by the direct action of steam until the fermentable sugars are formed, and so confining the heat that the mass is maintained throughout the entire operation in an unsaturated and absorptive condition.

In testimony whereof I affix my signature in presence of two witnesses.

Corrections in Letters Patent No. 1,032,448.

It is hereby certified that in Letters Patent No. 1,032,448, granted July 16, 1912, upon the application of George H. Tomlinson, of Chicago, Illinois, for an improvement in "Processes of Producing Fermentable Sugars from Cellulosic Materials," errors appear in the printed specification requiring correction as follows: Page 2, line 74, for the word "accompanying" read *accompanying*; page 3, line 112, after the word "digester," strike out the comma and insert the word *having*; and that the said Letters Patent should be read with these corrections therein that the same may conform to the record of the case in the Patent Office.

Signed and sealed this 8th day of October, A. D., 1912.

[SEAL.]

C. C. BILLINGS,
Acting Commissioner of Patents.

- a freely permeable condition to the direct action of steam under suitable pressure, in a closed vessel having an acid-resisting, heat-insulating and heat-retaining lining.
5. 3. The process of producing fermentable sugars from wood-waste or other cellulosic raw materials, which consists in heating the mass, in a freely permeable state and in presence of a suitable hydrolyzing agent, by
10. the direct action of steam admitted to the interior thereof, until the fermentable sugars are formed, and so confining the heat that the mass is maintained throughout the entire operation in an unsaturated and
15. absorptive condition.
4. The process of producing fermentable sugars from wood-waste and other cellulosic

raw materials, which consists in heating the mass, in a freely permeable state, by the direct action of steam, thereafter disseminating through it a suitable hydrolyzing agent, and continuing the heating by the direct action of steam until the fermentable sugars are formed, and so confining the heat that the mass is maintained throughout the entire operation in an unsaturated and absorptive condition.

In testimony whereof I affix my signature in presence of two witnesses.

GEORGE H. TOMLINSON.
